1 Claim

ABSTRACT OF THE DISCLOSURE

Complementary grooved resistant surfaces may be used to effect quiet non-backlash torque between a drum and drive assembly. The contact pressure between the surfaces may be maintained by a spring which may be compressed to facilitate the drum removal or installation.

BACKGROUND OF THE INVENTION

Rotating drums are frequently employed in various mechanical apparatus. In many such applications it is desirable or necessary to remove the drum from time to time to affect cleaning or loading of a roll of operating material. In a drum type plotter for example, it is desirable to have the drum secured in a mounting which will allow quick and easy removal without the use of tools or other specific components. In addition, the drum mounting must be maintained with precision alignment and centering. Furthermore, in order to assure the integrity of the plot, the coupling between the drum drive source and the drum must be positive and without backlash.

Accordingly, it is a primary object of the present invention to provide a positive coupling arrangement for a removable drum.

It is a further object of the present invention to provide an arrangement for mounting a rotatable drum which will allow the drum to be quickly and easily removed without the aid of tools.

It is another object of the present invention to provide a mounting arrangement for a removable drum which will facilitate both convenient centering of the drum and the maintenance of its positional alignment while in operation.

Other objects and advantages of the present invention will be obvious from the detailed description of a preferred embodiment given hereinbelow.

SUMMARY OF THE INVENTION

The present invention comprises a pair of accordant matting materials bonded between a drum and drive assembly for torque transmission therebetween. The drum and drive assembly are aligned with the mats by a center pin, the drum being spring loaded at the opposite end so as to effect a positive non-backlash type of pressure contact between the complementary mats. Removal of the drum is conveniently accomplished by depressing the spring load so as to enable the drum to clear the center pin.

DESCRIPTION OF THE DRAWINGS

FIG. 1 is a cross-sectional side view illustrating the operative elements of the invention.

FIG. 2 is a view of the matting material used for obtaining positive non-backlash drive.

2

DESCRIPTION OF A PREFERRED EMBODIMENT

Referring to the drawings and particularly to FIG. 1, a preferred embodiment of the invention comprises a hub 1 having bonded thereto a first corrugated matting surface 2 and a drum 6 having mounted to its drive end bell 4 a second corrugated matting surface 3. The matting material may be rubber or neoprene and the grooves may be similar to that used on floors or stairs for anti-slip purposes. A centering pin 5, which is attached to the hub 1, is utilized to align the drum 6 with the hub 1, the location of the valleys and peaks of the corrugated material being arranged so as to allow a mesh between the hub and drum when the drum is centered on the centering pin 5 as shown. The two pieces of corrugated matting 2 and 3 are held in mesh by the spring loading arrangement 8 which functions to maintain the accordant hills and valleys of the two surfaces in pressure contact thus forming a kind of "positive clutch." The spring loading arrangement 8 comprises a spring loaded flange 10 and tapered bearing support 9, the latter functioning as a support for the drum end bell 11 as shown.

FIG. 2 shows a cross-sectional view of a typical matting material. For positive non-slip traction, the slope of the valley walls at the midpoint should be at least 45 degrees. The hub piece 2 and the end bell piece 3 must of course be complementary, the respective hills and valleys having the relationship shown in FIG. 1.

In order to remove the drum, or remount it after it has been removed, it is only necessary to depress the spring loaded flange 10 to the right (in the direction of the arrow 13) so as to compress the load spring 14 a distance sufficient to allow the drive end bell 4 to clear the centering pin 5.

Although a preferred embodiment of the present invention has been shown and illustrated, it will be understood that numerous changes, modifications and substitutions may be made without departing from the spirit of the invention.

I claim:

1. An arrangement for mounting a removable drum comprising:
  - a rotatably mounted hub member having a resilient corrugated matting attached thereto;
  - a drum having a circular opening concentric with the cylindrical axis of said drum and a complementary corrugated resilient matting attached to one end of said drum;
  - a centering pin aligning said hub and drum with respect to said matting surfaces; and
  - a spring loaded flange having a protruding tapered bearing support surface openably fitting an opening in the other end of said drum for support thereof.
